CLOYDE H. SMITH, OF SAN JOSE, CALIFORNIA, ASSIGNOR OF ONE-HALF TO GEORGE M. MATZET, (NOW BY JUDICIAL CHANGE OF NAME GEORGE MICHAEL MALTON,) OF BROOKLYN, NEW YORK.

PRINTER'S REDUCING-GAGE.

1,330,353.

Specification of Letters Patent. Patented Feb. 10, 1920.

Application filed September 12, 1917. Serial No. 191,087.

To all whom it may concern:

Be it known that I, CLOYDE H. SMITH, a citizen of the United States, residing at San Jose, in the county of Santa Clara and State of California, have invented certain new and useful Improvements in Printers' Reducing-Gages, of which the following is a specification.

This invention relates to printers' appliances, and more particularly to printers' reducing gages.

The object of the invention is to provide a gage of this character for use in quickly reducing or enlarging drawings, illustrations, photographs, cuts and the like to an appropriate size for use in printing them in a predetermined space in a newspaper, magazine or the like without requiring any calculating or thought on the part of the user, whereby a large amount of time may be saved and the greatest accuracy attained in performing the work, and in which the width and depth of the illustration will remain constant.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a gage constructed in accordance with this invention,

Fig. 2 represents a transverse section taken on the line 2—2 of Fig. 1, and

Fig. 3 is a detail sectional view through the frame and clip 11.

In the embodiment illustrated, the device constituting this invention is shown in the form of a rectangular frame 1 constructed of any suitable material, preferably of flat metal strips and which may be finished in any suitable or desired manner. This frame has its top bar 2 and one side bar 3 thereof provided with indicia at one edge to indicate inches as shown at 4 and at the other edge agate lines as shown at 5, said inches and agate indicia being shown separated on each bar by a recess 6, one of which

extends longitudinally on the upper face of each of the bars 2 and 3. It is well known that substantially fourteen agate lines are employed to each inch.

The inch or agate markings or indicia are so formed as to permit convenient reading from the upper left hand corner to the lower right hand corner of the frame, a longitudinally yieldable divider being employed. This divider is composed of wire 7 having a helical spring 10 connected with one end thereof. The other end of this wire is connected with the upper left hand corner of the frame 1 by means of an eye 8 attached to said corner and which is connected with a coöperating eye 9 carried by the wire. The end of this wire 7 connected with spring 10 also has an eye 9' with which is connected one end of the helical spring 10, the other end of said spring carrying a spring clip 11 of any suitable construction which is adapted to be slid along the outer edge of the lower bar 12 of the frame and also along the outer edge of the right hand side bar 13 so as to divide diagonally any rectangular figures constructed upon the frame by means now to be described.

Two strips 14 and 15 are provided which are designed to intersect each other at right angles and to have their opposed ends hooked over the opposed bars of frame 1 as is shown clearly in Fig. 1. These strips 14 and 15 are alike except that the markings are reversed, each being provided along its side edges with indicia to indicate agate and pica lines as shown at 18 and 19, respectively, approximately fourteen agate lines being used to an inch and about six picas. These indicia are separated by any suitable means, longitudinally extending laterally spaced lines 20 being here shown.

The strip 14 has its opposite ends folded as shown in Fig. 2 to provide hooks as 16, the member 14 being designed to hook over the outer edge of the top bar 2 and the bottom bar 12 and to be moved along said bars to any desired point where it may be secured by means of a spring pressed pin 17 carried by one end thereof, the construction of which is shown in Fig. 2 and which pin is designed to enter the recess 6 of the bar 2. The lever 17a which carries pin 17 is depressed to release the pin and said pin snaps into engagement with the frame when pres-

sure on the lever is relieved. By so constructing this connector for strip 14 it will be obvious that the strip may be operated to adjust it to the desired position 5 with the least possible exertion on the part of the operator and with a minimum consumption of time, it being understood that speedy operation of the device is of utmost importance. The strip 15 correspondingly 10 hooks over the outer edges of the side bars 3 and 13 and is similarly provided with a spring pressed pin 17', which operates in the same manner that the pin 17 does, for securing strip 15 in adjusted position. It 15 will thus be seen that these two strips may be moved on the bars with which they are engaged and positioned to intersect at right angles at any desired point, according to the size of the picture to be reduced or enlarged. The wire 7 must overlie the strips 20 14 and 15 in order that said wire may be shifted in the manner above set forth.

In the operation of this device, when it is desired to reduce a drawing, say, of a size 25 twelve inches long by six inches wide, to occupy a space not more than four inches long, it would be necessary to determine how wide proportionately in agate lines the reduced drawing should be. In order to determine this with this gage, the drawing to be reduced should be placed beneath the gage so that its upper left hand corner would line up exactly with the upper left hand corner of the gage at a point where 30 wire 7 is fastened to the gage. Then this wire 7 is laid across the drawing, passing directly from the upper left hand corner of the drawing to the lower right hand corner thereof, thereby dividing the drawing 35 into two equal parts or angles. When this has been done, the strip 14 of the gage is moved over until the four inch point on the scale of the gage is reached. Then the strip 40 15 of the gage is moved until it intersects the strip 14 with wire 7 at the point of intersection. Then all that is necessary to ascertain how many agate lines long the drawing should be is to glance at the left hand scale of the gage, which will show the 45 exact number of lines which are necessary to be used and a glance to the top scale will disclose the width.

It will thus be seen that the use of this 50 device saves all mathematical calculations as will be clear to those versed in matters pertaining to printing and that a drawing may be reduced in size for use as a cut, with the sides having the same proportions to each other as the sides of the drawing 55 have to each other. This is accomplished by measuring off on the side bars 2 and 3 of frame 1 the lengths of two sides of the drawing to be reduced and then arranging the wire 7 so that it will extend across the 60 point of intersection of the bars 14 and 15.

The strips 14 and 15 are then shifted on the bars 2 and 3 to give the proper size for the cut, bearing in mind the fact that wire 7 must still extend directly over and across the point of intersection of the bars 14 and 15 regardless of their relative adjusted position. In this manner a rectangle is obtained bearing a true proportion to the size of the drawing to be reduced. 70

The device may be the same size as a 75 newspaper sheet so as to accommodate cuts varying in size from that of a newspaper sheet to one of very small size.

From the foregoing description, taken in connection with the accompanying drawings, the advantages of the construction and of the method of operation will be readily apparent to those skilled in the art to which the invention appertains and while I have described the principle of operation of the 80 invention together with the device which I now consider to be the best embodiment thereof, I desire to have it understood that the device shown is merely illustrative and that such changes may be made as are within the scope of the claimed invention. 85

I claim:—

1. A printers' reducing gage comprising a frame having indicia thereon, members 95 slideable on said frame and crossing each other at right angles to form a section to receive the drawing to be reduced, and a longitudinally yieldable divider carried by said frame and operable to intersect diagonally the section so formed.

2. A gage of the class described comprising a frame having two members arranged at right angles and suitable indicia carried thereby, adjustable means for dividing the interior of the frame into sections, a dividing wire pivotally connected at one end with one corner of said frame and having yieldable means at its other end for detachably engaging the frame at a point remote from its point of attachment.

3. A gage of the class described comprising a rectangular frame having suitable indicia carried by two of the adjacent members thereof, adjustable means for dividing the interior of the frame into sections, a divider pivotally connected at one end with one corner of said frame and having means at its other end for detachably engaging the frame at a point remote to its point of attachment, said divider being longitudinally yieldable to facilitate its adjustment.

4. A gage of the class described comprising a rectangular frame having suitable indicia carried by two of the adjacent members thereof, adjustable means for dividing the interior of the frame into sections, a wire pivotally connected at one end to the corner of the frame formed by said members, a clip, and a helical spring arranged between and connecting said clip and wire.

to provide for the yieldable connection of the wire to the frame at a point remote from its pivotal connection with the frame.

5. A gage of the class described comprising a rectangular frame having indicia on its upper and one side bar thereof, a pair of strips having indicia thereon, said strips each having a hook at one end for engaging the outer edges of one of the bars 10 of said frame, said strips intersecting each other at right angles, spring pressed means

for adjustably connecting said strips to said frame, and a dividing wire adapted to diagonally divide the sections formed by said intersecting strips and the frame. 15

In testimony whereof I affix my signature in presence of two witnesses.
